Inventor,
Charles M. Spangler
By J. M. Spangler Atty.

UNITED STATES PATENT OFFICE.

CHARLES M. SPANGLER, OF EMPORIUM, PENNSYLVANIA.

BOILER-FLUE TOOL.

1,391,862.

Specification of Letters Patent. Patented Sept. 27, 1921.

Application filed May 4, 1921. Serial No. 466,722.

To all whom it may concern:

Be it known that I, CHARLES M. SPANGLER, a citizen of the United States, residing at Emporium, in the county of Cameron and

5 State of Pennsylvania, have invented certain new and useful Improvements in Boiler-Flue Tools, of which the following is a specification.

This invention relates to tools for bending 10 down the flanged ends of boiler flues so that the latter may be removed from the flue sheets.

Heretofore the common practice has been to use a cold chisel and hammer for this 15 purpose but this has been a slow operation with incident damage to the flue sheets. It has also been proposed to provide tools having jaws for bending down the flanged ends. Tools of this character, however, have not 20 had that degree of adjustability and efficiency demanded to meet various conditions and sizes of flues and flanges, so far as I am aware.

My object is to provide a tool adapted for 25 bending down the flanges of boiler flues to release them from the flue sheets, without possibility of damage to the flue sheets and which will be of such improved, adjustable, construction that it may be used in connection 30 with various sizes of flues and flanges and will meet substantially all conditions encountered.

In carrying out my invention I provide a handle or lever which has a jaw of improved 35 form adapted to be inserted in the flue and to serve as a fulcrum, combined with a bending jaw of improved form, and a yoke which embraces the lever and the shank of the bending jaw, there being provided clamp- 40 ing or securing means, first, to hold the yoke in any position to which it may be ad- justed on the handle or lever and, second, to hold the bending jaw in any position to which it may be adjusted in relation to the 45 handle or lever.

The invention is set forth more fully hereinafter and its novel features are recited in the appended claims. I am aware that means other than those shown may be employed for securing the yoke to the handle or lever and the bending jaw to the yoke and I do not, therefore, limit myself to the specific features of the invention shown in the drawing and hereinafter described, except 55 where recited in the claims.

In the accompanying drawing:

Figure 1 is a side elevation of the complete tool, illustrating how it is used.

Fig. 2 is an end elevation at the jaw end of the tool.

Fig. 3 is a detail perspective of the bending jaw.

Fig. 4 is a detail cross section through the fulcrum jaw; and

Fig. 5 is a plan view.

The handle or lever 1 is of suitable length to afford adequate leverage and is provided with a squared part 1^a having a jaw 2 which is rounded or notched at 3 and terminates in a rounded fulcrum 4. The jaw 2 may be 70 narrower than the width of the squared portion 1^a to facilitate the rocking of the handle or lever only from the fulcrum 4.

The bending jaw 5 has a squared shank 5^a of the same width as the squared part 1^a 75 and it rests against the latter, being held by a yoke 6 which embraces the squared parts 1^a and 5^a. A screw or fastening device 7 serves to clamp the yoke 6 to the squared part 1^a; a screw or fastening device 80 8 carried by the yoke serves to clamp the squared part 5^a to the yoke. Consequently the yoke 6 and jaw 5 may be adjusted as a unit in relation to the handle 1, and, further, the jaw 5 may be adjusted within, or through 85 the yoke 6. The first adjustment described enables the yoke and jaw 5 to be set to the position generally required and then a finer adjustment of the jaw 5 is obtained by loosening the screw 8 and shifting the jaw 90 5 inside of the yoke 6 and tightening screw 8.

The jaw 5 has its bending or gripping end offset from jaw 2 and suitably cut out or curved as at 5^b to afford proper clearance 95 between itself and the notched or cut away portions 3 to accommodate the flange or bead on the flue. The jaw is provided with a sharp or chisel-like edge 9 and its end 10 is sloped backwardly so as not to contact 100 with the flue sheet and to permit the sharp edge 9 to take hold of the flange on the flue precisely where the edge of said flange is bent against the flue sheet.

The tool is operated as shown in Fig. 1, 105 after suitable adjustment. The fulcrum 4 bears against the inside of the flue and the chisel-shaped edge 9 works down between the edge of the flange on the flue and the flue sheet so that the flange is bent down 110

and the flue can be readily removed after the flanges or beads at both of its ends are thus bent.

The jaw 5 is narrowed or tapered from 5 side to side to afford a sufficiently wide edge 9 and yet one which is not so wide that it will interfere with proper engagement with the flange of the flue.

My tool affords an easily operated and 10 convenient device for the purpose set forth without any danger of nicking or injuring the flue sheets and saves a great deal of time which is required when a cold chisel is used.

15 I claim:

1. A boiler flue tool comprising a lever or handle provided with a jaw having a fulcrum adapted to engage the inner surface of the flue which is to be removed, a bending 20 or prying jaw adapted to engage the outer flange of the tube, said jaw being slidable lengthwise of the lever or handle aforesaid for the purpose of positioning it as desired in relation to the jaw and fulcrum, and a 25 yoke embracing the shanks of the aforesaid jaws and provided with means for locking the bending jaw.

2. A boiler flue tool comprising a lever or

handle provided with a jaw having a fulcrum adapted to engage the inside of the 30 flue, a bending jaw slidable lengthwise of the lever or handle aforesaid for the purpose of positioning it as desired in relation to the jaw and fulcrum, a yoke embracing the shanks of the two jaws aforesaid, means 35 for securing the yoke to the shank of the handle or lever, and means for securing the bending jaw to the yoke, whereby the yoke and bending jaw may be adjusted as a unit on the shank of the handle and the bending 40 jaw may also be independently adjusted inside of the yoke.

3. A boiler flue tool comprising a handle or lever having a notched jaw terminating in a fulcrum, and a bending jaw whose shank 45 is adjustable lengthwise of the lever or handle and is provided with an offset jaw end having a chisel-like extremity which is adapted to overhang the notched part of the jaw on the handle and is for the purpose 50 of engaging the flange on the flue to pry or bend it away from the flue sheet when the handle is rocked on the fulcrum aforesaid.

In testimony whereof I affix my signature.

CHARLES M. SPANGLER.
